(57) **CLAIM**

The ornamental design for a food container, as shown and described.

DESCRIPTION

FIG. 1 is a perspective view of a first embodiment of a food container, showing my new design;

FIG. 2 is another perspective view thereof;

FIG. 3 is still another perspective view thereof;

FIG. 4 is a top elevation view thereof;

FIG. 5 is a bottom plan view thereof;

FIG. 6 is a front elevation view thereof;

FIG. 7 is a rear elevation view thereof;

FIG. 8 is a left side elevation view thereof; and

FIG. 9 is a right side elevation view thereof.

FIG. 10 is a perspective view of a second embodiment of a food container, showing my new design;

FIG. 11 is another perspective view thereof;

FIG. 12 is still another perspective view thereof;

FIG. 13 is a top elevation view thereof;

FIG. 14 is a bottom plan view thereof;

FIG. 15 is a front elevation view thereof;

FIG. 16 is a rear elevation view thereof;

FIG. 17 is a left side elevation view thereof; and,

FIG. 18 is a right side elevation view thereof.

The broken line shows unclaimed elements of the food container for the purpose of illustrating portions of the article and forms no part of the claimed design.
